UNITED STATES PATENT OFFICE

ROYAL W. GUDGEN AND JOSEPHINE A. GUDGEN, OF FORT LAUDERDALE, FLORIDA

DESIGN FOR A DOLL

Application filed April 16, 1932. Serial No. 43,523. Term of patent 7 years.

To all whom it may concern:

Be it known that we, ROYAL W. GUDGEN and JOSEPHINE A. GUDGEN, citizens of the United States, residing at Fort Lauderdale, in the county of Broward and State of Florida, have invented a new, original, and ornamental Design for a Doll, of which the following is a specification, reference being had to the accompanying drawing, forming part thereof.

Figure 1 is a view in front elevation of the doll showing our new design;

Figure 2 is a rear view of the same;

Figure 3 is a view in side elevation.

We claim:

The ornamental design for a doll, as shown.

ROYAL W. GUDGEN.
JOSEPHINE A. GUDGEN.
